UNITED STATES PATENT OFFICE.

HENRY PAUROWICZ, OF CHICAGO, ILLINOIS.

DESIGN FOR A CAKE-STAND.

No. 38,140.

Specification for Design.

Patented July 31, 1906.

Application filed February 12, 1906. Serial No. 300,809. Term of patent 7 years.

To all whom it may concern:

Be it known that I, HENRY PAUROWICZ, a citizen of the United States, residing at Chicago, in the county of Cook and State of Illinois, have invented a certain new, original, and ornamental Design for a Cake-Stand, reference being had to the accompanying drawings, forming a part of this specification.

Figure 1 of the drawings is a front elevation, and Fig. 2 a perspective view, of a cake-stand embodying my invention.

What I claim is—

The ornamental design for a cake-stand, as shown.

HENRY PAUROWICZ.
